UNITED STATES PATENT OFFICE

124,662

DESIGN FOR A PUZZLE

John D. Boyle, Greenwich, Conn.

Application November 5, 1940, Serial No. 96,344

Term of patent 3½ years

To all whom it may concern:

Be it known that I, John D. Boyle, a citizen of the United States, residing at Greenwich, Fairfield County, State of Connecticut, have invented a new, original, and ornamental Design for a Puzzle, of which the following is a specification, reference being had to the accompanying drawing, forming part thereof.

Fig. 1 is a front view of a puzzle, showing my new design.

Fig. 2 is a side view.

Fig. 3 is a top plan view and

Fig. 4 is a back view of the same.

I claim:

The ornamental design for a puzzle, substantially as shown.

JOHN D. BOYLE.
